[57] CLAIM

The ornamental design for a tire chain for slip prevention of vehicle, as shown.

DESCRIPTION

FIG. 1 is a top perspective view of a tire chain for slip prevention of vehicle showing my new design;

FIG. 2 is an enlarged fragmentary top plan view thereof;

FIG. 3 is an enlarged fragmentary bottom plan view thereof;

FIG. 4 is a sectional view thereof taken along line IV—IV of FIG. 3; and

FIG. 5 is an enlarged fragmentary top plan view of the shackle end thereof.
